US00D600818S

(12) **United States Design Patent**
Yang

(10) **Patent No.:** **US D600,818 S**
(45) **Date of Patent:** **** Sep. 22, 2009**

(54) **VIBRATING TOE STRETCHER**

6,481,443 B1 11/2002 Moore-Johnson et al.
D481,828 S 11/2003 Goldberg et al.

(75) Inventor: **Jun Yang**, Zhejiang (CN)

(73) Assignee: **International Edge, Inc.**, Fairfield, NJ
(US)

(**) Term: **14 Years**

(21) Appl. No.: **29/314,044**

(22) Filed: **Feb. 27, 2009**

(51) LOC (9) Cl. **28-03**

(52) U.S. Cl. **D24/215**

(58) Field of Classification Search **D24/200, D24/212–214, 215; D21/680; 601/23, 27, 601/29–35, 49–50, 56–57, 84–86, 93, 97–98, 601/101, 40, 118, 131, 135–138; 482/44, 482/47, 59–50, 97**
